EDUCATIONAL GEOMETRIC PUZZLE

Simon Gompes and Herman Schpektor, both of Nieuwe Keizersgracht 58, Amsterdam, Netherlands

Filed Mar. 10, 1969, Ser. No. 16,163
Claims priority, application Great Britain Feb. 7, 1969

Term of patent 14 years

Int. Cl. D19—08

U.S. Cl. D25—1

Fig. 2.

FIG. 1 is a plan view of an educational geometric puzzle showing our new design with a sample piece shown exploded therefrom;

FIG. 2 is an elevational view thereof, as viewed in the direction of the arrow 2 in FIG. 1; and

FIG. 3 is a section on the line 3—3 of FIG. 1.

We claim:

The ornamental design for an educational geometric puzzle, substantially as shown.
